D11-23.

OR D12,374

EX

UNITED STATES PATENT OFFICE.

JAMES WILKINSON, OF MOUNT VERNON, NEW YORK.

DESIGN FOR A BRACELET.

SPECIFICATION forming part of Design No. 12,374, dated July 26, 1881.

Application filed June 22, 1881. Term of patent 3½ years.

To all whom it may concern:

Be it known that I, JAMES WILKINSON, a citizen of the United States, residing at Mount Vernon, in the county of Westchester and State of New York, have invented and produced a new and original Design for Bracelets, of which the following is a specification, reference being had to the accompanying photographs, forming part thereof.

- 5 10 This invention relates to a design for a bracelet consisting of oblique bars so arranged that the obliquity of the bars shall be in a different direction on the inner circumference of the bracelet from the direction of those which compose the outer circumference, thus giving the bars of the bracelet the appearance of crossing each other at an angle, thereby presenting an ornamental double lattice-work appearance.
- 15 20 This invention is illustrated in the accompanying drawings, in which Figure 1 repre-

sents a perspective view of my bracelet when opened and drawn out in right line. Fig. 2 is a similar view of the same when closed.

Similar letters indicate corresponding parts. 25

In the drawings, the letters *a b* designate the double oblique bars, inclined across each other, as shown.

What I claim as new, and desire to secure by Letters Patent, is— 30

The design for a bracelet, substantially as above described and shown, consisting of double oblique bars arranged across each other in the body of the bracelet.

In testimony whereof I have hereunto set my 35 hand and seal in the presence of two subscribing witnesses.

JAMES WILKINSON. [L. S.]
